UNITED STATES PATENT OFFICE.

MATTHEW VIERENGEL, OF BROOKLYN, NEW YORK.

ENVELOP-MACHINE.

1,000,057.

Specification of Letters Patent. Patented Aug. 8, 1911.

Application filed April 27, 1910. Serial No. 557,879.

To all whom it may concern:

Be it known that I, MATTHEW VIERENGEL, a citizen of the United States, and a resident of the borough of Brooklyn, county of Kings, State of New York, have invented 5 certain new and useful Improvements in Envelop-Machines, of which the following is a specification.

The present invention relates to improvements in the type of envelop machines in which previously cut blanks are passed through suitable forming, creasing and pasting mechanisms for folding, creasing and pasting the side and end flaps. Machines 10 of this type can be arranged to operate in conjunction with an automatic feeding machine for supplying successive blanks from an adjustably mounted pile, or they can be arranged to operate in conjunction with suitable blank cutting mechanism by which the successive blanks are cut from continuous 15 rolls of paper. I prefer to employ my invention in conjunction with an automatic paper feeding machine in which the previously 20 prepared blanks are supported in an adjustably mounted feeder and successively separated and passed to the blank feeding mechanism of the envelop machine.

The main object of my present invention 25 is to provide a simple and effective envelop machine which is capable of ready adjustment for making envelops of various sizes and which, by a simple interchange of certain of the final parts of the mechanism, can be adapted to the manufacture of different 30 styles of envelops. The general construction of my machine is the same for making both a center seam envelop and a side seam envelop, the modifications required for these two 35 forms of envelops being in the arrangement of the creasing and pasting devices as will hereinafter appear.

In general construction, my improved envelop machine comprises an endless traveling belt provided with a central series of 40 automatically operated grippers adapted to take the leading edge of the successive blanks from an automatic paper feeding machine and convey the blanks through the side fold 45 forming devices and deliver the formed blanks to the final creasing and sealing devices. The automatic feeding machine is arranged to deliver the blanks to a gripper cylinder which carries them forward to suitable 50 transferring feeding devices from which

they are taken by the grippers upon the endless belt.

In making the center seam form of envelop, the blank is carried by the gripper cylinder under a single pasting roll for applying a line of paste upon the inner face of one of the broad side flaps prior to the passage of the blank through the side fold forming mechanism, which folds inwardly the two side flaps with the pasted flap on top 60 preparatory to the action of the center seam pressure sealing device. The transferring feeding devices engage the blank along a central longitudinal plane so as not to interfere with this line of paste upon one of the 65 side flaps. After the formation of the center seam in this manner, the partly formed envelop is conveyed to the bottom flap creasing device and the bottom flap pasting device and then through suitable pressure devices 70 for folding over the pasted bottom flap and sealing and completing the envelop. If the envelop is formed with a top flap, the final action of the machine is to transversely crease 75 said top flap to cause it to fold over accurately.

In the manufacture of the side seam envelop, the preliminary pasting roll is removed or put out of action and no paste is applied until after the blank has passed the 80 side fold forming mechanism, and the end flap creasing device. With this form of envelop, two lines of paste are applied to the inwardly folded narrow side flaps and the long bottom flap is carried over and pressed 85 against the two lines of paste upon said inwardly folded side flaps.

The main conveyer belt, which takes the blanks from the transfer feeding devices leading from the automatic feeding machine, 90 is formed with a series of transverse cleats upon its inner face which engage in sockets or recesses formed in parts of the peripheries of the supporting and operating wheels or pulleys. These transverse cleats are formed 95 in sections to enable their engaging portions to be adjusted longitudinally of the belt to facilitate the accurate adjustment of the belt upon said supporting wheels or pulleys to properly time the action of the grippers. 100 The conveying belt is preferably a broad leather belt having the conveying grippers arranged in slots cut through it in its central longitudinal plane at equal distances apart. Each gripper is pivotally mounted upon 110

brackets secured to the inner face of the conveying belt, said brackets being provided with friction rollers which run upon suitable track bars extending longitudinally of the machine parallel with the carrying portion of the belt. The grippers are actuated by means of stationary cam tracks by which they are opened and closed at the proper points to take and deliver a blank.

10 One of the most important features of my present invention is the construction of the mechanism for imparting the transverse creases to the end flaps of the envelop. In envelopes having a top flap, there are of course two transverse creases formed, whereas, in envelopes having no top flap, there is but a single transverse crease formed in the bottom flap. One set of the creasing devices (comprising coöperating male and female members, arranged respectively above and below the plane of feed), has a certain timed relation to the grippers of the blank feeding mechanism, to form the crease between the body of the envelop and the flap at the bottom of the envelop, whether the bottom flap be a narrow one as in the center seam envelop, or a broad one of the whole length of the envelop as in the side seam envelop. The other set of transverse creasing devices comprises male and female members removably mounted in adjustable rotary carrying frames, arranged respectively above and below the plane of feed, so that their use can be dispensed with when making envelopes without the top flap. The top flap creasing devices are adjustable circumferentially of their carrying frames to place them closer to or farther away circumferentially from the bottom flap creasing devices to facilitate the manufacture of envelopes of different sizes. In carrying out this adjustable idea of this part of my machine, I provide each carrying frame with two or more segmental frame pieces upon a rotary shaft with a plurality of dove-tail sockets or pockets in their peripheries to receive the adjustable male and female creasing bars. The creasing bars can be mounted in any of said dove-tail sockets or pockets to place them at approximately the desired distance circumferentially from the bottom flap creasing members, the requisite final adjustment being accomplished by adjusting the segmental frame pieces upon their shafts. This under rotary frame of the creasing devices also carries automatic grippers which are designed to engage the folded side edges of the blanks after the completion of the center seam in the one form of envelop, and prior to the formation of the side seam in the other form of envelop. In the form of the machine for the center seam envelop, there is a bottom flap pasting device carried by the upper rotary sectional frame referred to, which imparts a line of

paste upon the bottom flap simultaneously with the formation of the bottom flap crease in that form of envelop. This bottom flap pasting device comprises a spring blade projecting from a rock shaft journaled in two of the arms of said upper rotary frame and controlled by a rock arm which runs in peripheral engagement with a stationary cam so that once in each revolution of said frame, said spring pasting blade will be thrown into peripheral engagement with a pasting roll operating in a paste reservoir and then be carried around and wiped against the projecting bottom flap at the moment the bottom crease is made. 80

The grippers upon the under rotary sectional frame are designed to move radially and longitudinally of their supporting frame for the purpose of moving them into and out of engagement with the blank. The exact construction of said gripping mechanism will be hereinafter more fully explained. 85

In arranging my machine for the manufacture of side seam envelopes, I remove the paste receptacle and roller of the preliminary form and mount a substitute paste roller in an extended pair of brackets arranged lower down than the brackets of the first form of pasting device, and mount upon a suitable shaft a pair of paste applying segments for imparting to the two narrow infolded side flaps, two lines of paste against which the side edges of the long bottom flap are pressed to complete the envelop. 90 95 100

The delivery mechanism of my improved machine may be of any approved construction.

In order that my invention may be fully understood, I will first describe the same with reference to the accompanying drawings, and afterward point out the novelty more particularly in the annexed claims. 105

In said drawings: Figure 1 is a side elevation of my improved envelop machine in the form adapted to the manufacture of center seam envelopes. Fig. 2 is a plan view of the same. Fig. 3 is an enlarged vertical longitudinal sectional elevation of the front part of my machine, showing particularly the automatic feeding machine and devices for transferring the successive blanks from the pile to the endless conveyer belt. Figs. 4 and 5 are detail views of the main parts of the automatic feeding machine, showing different positions of the operative parts. Fig. 6 is a detail front elevation of the automatic picker and separating finger of the feeding machine. Fig. 7 is a view similar to Fig. 3 of the rear part of the machine. Fig. 8 is a vertical longitudinal sectional view of the main endless conveyer belt and grippers. Fig. 9 is a detail vertical sectional view of part of the same with parts 110 115 120 125 130

broken away. Fig. 10 is a detail perspective view showing one of the adjustable cleats upon the endless conveying belt. Figs. 11, 12, 13, 14, 15 and 16 are diagrammatic views illustrating the different stages in the manufacture of a central seam envelop by my machine, starting with the blank and ending with the completed envelop. Fig. 17 is a view similar to Fig. 7 showing a slight modification of my improved machine to adapt it to the manufacture of side seam envelops. Fig. 18 is a rear view of the machine illustrated in Fig. 17, parts being broken away for the sake of clearness. Fig. 18^a is a detail edge view of one of the gripper operating cams of the creasing and end flap forming mechanisms. Figs. 19, 20, 21, 22 and 23 are diagrammatic views illustrating the several stages in the formation of side seam envelops by any machine, beginning with the blank and ending with the completed envelop.

My improved machine may be built upon any suitable framework capable of properly supporting the operative parts hereinafter described. As shown, the machine frame consists chiefly of two main side frames indicated by reference numerals 1 and 2. These side frames are suitably braced by transverse bars, tie rods and shafts which will be referred to specifically in the following specification only when necessary to point out some particular feature.

Extending horizontally between the main side frames 1 and 2 from points adjacent to the opposite ends is a main table or platform 5 upon which the adjustable side fold forming mechanism is mounted, and over which the endless gripper belt travels in the manner presently to be explained. Leading to the endless gripper belt is a main transferring feeding device which takes the successive blanks from an adjustably mounted pile and transfers them to the grippers upon said endless belt. As stated above, an automatic sheet feeding machine may be employed in conjunction with my improved envelop machine, or a suitable form of blank cutting mechanism may be provided for operating upon a continuous web of paper to supply successive blanks to the conveying devices of my machine. I have illustrated my improved machine equipped with an automatic feeding machine which is designed to separate the successive blanks from a pile and pass them to the feeding devices of the envelop machine. The structure of this automatic feeding machine is covered by my divisional application Serial No. 586,488, filed October 11, 1910, and forms no part of the invention of the present case.

The feeding machine will now be described.

10 is the pile supporting table of the automatic feeder. This table 10 is mounted in

inclined position between two rigid side bars 11 on which slide perforated ears or lugs 12 projecting from side frames 13 of the table 10. A small sprocket wheel 15 is journaled upon a block 16 secured to one of the rigid 70 bars 11, and an endless sprocket chain 17 passes around the sprocket wheel 15 and around a similar sprocket wheel 18 keyed to a shaft 19 carrying a larger sprocket wheel 20 and journaled in suitable bearings on the 75 side frames of the machine. The larger sprocket wheel 20 is driven by a sprocket chain 21 passing around a small sprocket wheel 22 fixed to a ratchet wheel 24 journaled upon a stud 23. The shaft 19 extends 80 from side to side of the machine and the parts 15, 16, 17 and 18 are duplicated at the opposite side of the machine. The sprocket chains 17 have secured to each of them a block 25 pivoted to one of the side frames 13 85 of the table 10, so that the gradual upward movement of table 10 is accomplished by the movement of sprocket chains 17. A gravity pawl 30 journaled at 31 rests constantly in engagement with the ratchet wheel 24 to 90 prevent retrograde movement. An actuating pawl 32 is pivoted at 33 upon a lever 34 journaled to the side frame at 35 and carrying at its lower end an anti-friction roller 36 operating in peripheral contact with a cam 37 keyed to the cylinder shaft 38 extending from side to side of the machine frame and driven in the manner hereinafter explained. The actuating pawl 32 rests upon a controlling plate 40 which is supported by a pin 41 100 just above the ratchet wheel 24 and movable forwardly and backwardly thereover. This controlling plate 40 is pivoted at 43 to the upper end of a rock arm 44 keyed to a shaft 45 journaled in stationary bars 11 and extending transversely above the top of the pile of blanks. Secured to shaft 45 are the forwardly presented gage arms 46 which are designed to rest upon the top blank of the pile. These gage arms have upwardly curved fingers 47 against which the forward portion of the blanks are bent upwardly by the separating mechanism in the manner presently to be explained. From this construction of pile elevating mechanism, it will be observed that when the pile is at the proper height for the operation of the separating and feeding devices, the controlling plate 40 will support the actuating pawl 32 105 out of engagement with the ratchet wheel 24. When the top surface of the pile falls below the required height, the downward movement of gage arms 46 will lower the rock arm 44 and move the controlling plate 40 forwardly to permit the actuating pawl 32 to engage a tooth of ratchet wheel 24 on its next rearward stroke under the action of cam 37 to impart a lifting impulse to the sprocket chains 17. 110

The pile of blanks B mounted upon the 130

table 10 are supported at the rear by inclined gage rods 50 which are mounted at their upper ends upon blocks 51 threaded upon adjusting screws 52 suitably journaled in the side frames of the machine. These gage rods 50 operate in slots (not shown) in the table 10. By rotating the screws 52 by any suitable means, as illustrated, the gage rods may be adjusted to support larger or smaller blanks.

The sides 1 and 2 at the front of the machine overhang the automatic feeding machine, and the operative parts of said machine are mounted thereon. Vertical guide fingers 60 extend from a frame bar 61 in position to engage the angular recesses *b* of blanks B. Angular pile holding fingers 62 engage the top of the pile of blanks at opposite sides of the projections forming the bottom flap of the envelop. The engagement of the pile with said fingers 62 is maintained by the pile elevating mechanism.

Extending transversely of the machine at its forward end is a cam shaft 70 suitably journaled in the machine side frames and carrying at one end a sprocket wheel 71 over which operates a sprocket chain 72 driven by a sprocket wheel 73 keyed to the shaft 38 above referred to. By this means the cam shaft 70 is constantly rotated. The shaft 70 carries three cams 75, 76 and 77 for operating the blank separating devices in the manner which will now be explained.

A rock shaft 80 is suitably journaled in the side frames of the machine parallel with the cam shaft 70 and a rock arm 81 extends forwardly and downwardly from the shaft 80 in the central longitudinal plane of the machine and has pivotally connected at 82 an upwardly extending plate 83 formed with a bifurcated upper end 84 in which is pivotally mounted a suction finger 85. The arm 81 journaled upon shaft 80 is formed integral with or otherwise rigidly connected with an oppositely extending arm 81^a carrying in its free end an antifriction roller 81^b which operates in peripheral engagement with the cam 76 above referred to.

The suction finger 85 is hollowed out and formed with a blank engaging suction cup in its under face in a manner well understood in this art and the tubular structure of said suction finger 85 is connected with a flexible hose 86 extending to an ordinary suction pump 87 pivotally mounted upon the frame at 88 and provided with an actuating piston rod 89 connected with a crank 90 driven by any suitable part of the machine.

The suction finger 85 has pivotally connected to a downwardly projecting lug 85^a a rod 91 adjustably and pivotally mounted upon the forward end of a lever 92 journaled at 93 and carrying an anti-friction roller 94 operating upon the cam 75 above referred to.

A link or pitman 96 is pivoted at 97 to the plate 83 and extends forwardly to the shaft 70 on which it is guided. This pitman 96 carries an anti-friction roller 98 operating upon the cam 77 above referred to.

The rock shaft 80 has rigidly secured to it the upwardly projecting arms 100 and 101 arranged at an angle to each other. The arm 101 has pivoted to it at 102 a pitman 103 extending rearwardly to the shaft 38 upon which it is guided, and carrying an anti-friction roller 104 operating in peripheral contact with a cam 105 keyed to said shaft 38. A spring 106 connecting pitman 103 with the machine frame causes said pitman to closely follow the movements of said actuating cam.

There are two or more upwardly presented arms 100 upon the rock shaft 80 between the side frames of the machine, and journaled in the upper ends of said arms 100 is a shaft 110 having secured to it in the central longitudinal plane of the machine a bifurcated separating finger 111. The two parts of the separating finger 111 operate in the grooves 112 cut in the opposite edges of the plate 83 of the suction separating finger and are guided thereby in their movements inwardly and outwardly over the pile and are carried by the plate 83 when said plate is elevated and lowered. The separating finger 111 is formed with upwardly inclined portions 111^a to form with the main part of the finger angular catches to engage the front edge of a blank for raising it from the pile, and moving it backward and upward into position to be taken by the cylinder grippers. This freely journaled shaft 110 has secured to it an upwardly projecting rock arm 115 which rests against an anti-friction roller 116 journaled upon a block 117 secured to the machine frame. A torsion spring 118 is coiled upon said shaft 110 with its opposite ends secured respectively to a collar upon the shaft and a stationary point for giving the shaft a spring tendency to move in one direction, holding the arm 115 yieldingly in engagement with roller 116 for the purpose which will presently appear.

Referring briefly to the operation of this automatic blank feeding mechanism, it will be observed that the cams 75, 76 and 77 cause the suction separating finger 85 to successively assume the positions illustrated in Figs. 4, 5 and 3. While the suction finger is performing these movements, the separating finger 111 is moved from the position shown in Fig. 4 to the position shown in Fig. 3, the final rearward movement under the action of cam 105 and spring 106 causing the separating finger to engage the edge of the blank and force it rearwardly to the position shown in Fig. 3, that is, curved up against the guide fingers 47. The partly

separated blank is held in this position until taken by the blank delivery mechanism which will now be described.

Journalized in the machine side frames 5 above the pile of blanks in the automatic feeding mechanism just described, is the transverse cylinder shaft 38 above referred to. The shaft 38 has secured to it a plurality of transversely adjustable wheels or 10 pulleys 125 constituting a sectional feed cylinder. The wheels or pulleys 125 are adjustably secured to shaft 38 by any suitable means such as set screws 125^a shown in dotted lines in Fig. 3. Two of said wheels 15 or cylinder sections 125 are formed with gripper slots or openings 126 through which project the curved gripper fingers 127 mounted upon a rock shaft 128 journaled in arms 129 adjustably secured to shaft 38. 20 Arms 129 are adjustably secured to shaft 38 by any suitable means such as set screws 129^a shown in dotted lines in Fig. 3. This gripper shaft 128 carries a small gear wheel 130 in constant mesh with a gear segment 25 131 journaled at 132 upon an arm 133 also secured to shaft 38. The gear segment also carries an antifriction roller 134 which runs in peripheral engagement with a stationary cam 135 secured to the side frame of the 30 machine and through which the shaft 38 extends. A torsion spring 127^c encircling shaft 128 has one end secured to the shaft and the other end secured to one of the arms 129 to give said shaft a gripper-closing movement and to hold roller 134 in engagement with cam 135. The arms 129 can be adjusted independently around the shaft 38 within certain limits to properly register the blank upon the gripper cylinder, that 35 is, to cause the blank to assume proper position with its longitudinal axis parallel with the direction of travel. The grippers 127 are also adjustable transversely of the machine upon their shaft 128 by means such 40 as set screws 127^b, and the cylinder sections 125 are similarly adjustable transversely of the machine upon their shaft 38 to adapt the machine to the manufacture of envelopes of different sizes. 45 The pair of gripper fingers 127 project rearwardly with reference to the direction of travel of the feed pulleys 125, and each finger is formed with a curved gaging face 127^a which engages the edge of the blank. 50 and crowds the blank backwardly in the closing movement so as to accurately register the blank in the bite of the grippers. In the position shown in Fig. 3 of the drawings, the gripper fingers 127 are just about 55 to close upon the raised edge of a blank, which is held in position for the engagement of the gripper fingers by the separating finger 111. Immediately after the position shown, the grippers close upon the blank 60 and as the sectional gripper cylinder rotates 65

in the direction indicated by the arrow, the blank is drawn from the top of the pile and carried upwardly beneath the curved guide rod 140 and delivered beneath the small frictional feed rollers 145 keyed to a shaft 146. 70 The rollers 145 engage the blank against the rotating gripper cylinder 125, and when the blank is properly engaged by the rollers 145, the cam 135 releases the grippers 127 from the blank and permits the blank to be 75 stripped from cylinder 125 and fed over the guide plates 150 into the bite of upper and lower frictional feed rollers 151 and 152 upon transverse shafts 153 and 154 which are driven by suitable gearing with 80 the shafts of the gripper cylinder and the endless gripper belt in any suitable manner.

The blank B taken from the automatic feeding machine by the gripper cylinder in the manner above described passes upwardly 85 around said cylinder with its side flaps projecting laterally beyond the ends of the cylinder. The side flap at one side of the machine passes between a grooved pressure roller 155 adjustably secured to the cylinder 90 shaft 38 by means such as set screws 155^a, and a paste applying disk 156 adjustably secured to a transverse shaft 157 journaled in the removable brackets 158 secured to the machine side frames. The disk 156 is adjustably secured by means such as set screw 95 156^a. This paste applying disk 156 is constantly rotated by any suitable means, such, for instance, as the gear wheel 159 keyed to the end of shaft 157 and meshing with 100 a similar gear 160 keyed to the end of shaft 38.

161 is a paste reservoir into which the periphery of the paste disk 157 projects to take up a film of paste and apply it in a thin zone along the edge of the blank which passes between disk 156 and grooved roller 155. The roller 155, disk 156 and paste box 161 are capable of adjustment transversely of the machine to apply the zone of paste 105 along the edge of the blank for any size of blank that is to be made up into a center seam envelop. The shaft 157 carrying disk 156 can be removed from the machine by the detachment of the journal brackets 158 110 when the machine is to be changed into the form for making side seam envelopes, or said shaft and disk can be allowed to run idly. 115

The curved guide plate 140 which is arranged parallel with the surface of the gripper cylinder 125, is extended rearwardly of the machine to a horizontal plate 140^a to a point above the first sectional cylinder of the endless gripper belt presently to be explained. This guide plate 140^a separates the 120 pairs of upper friction rollers 145 and 151. 125

165 and 166 are transverse shafts suitably journaled in the side frames of the machine and each carrying a sectional belt supporting and driving cylinder made up of wheels 130

167 and 168 as shown particularly in Figs. 8 and 9 of the drawings. The outer sections 167 of each of these cylinders are plain wheels or pulleys, while the section 168 is a similar wheel or pulley formed with transverse slots 169 to engage with cleats upon the inner surface of the endless gripper belt 170, and a cut-out portion 169^a, to permit the passage of the grippers and connected parts.

170 is an endless gripper belt formed preferably of leather with a series of cleats 171 secured to its inner surface. The belt 170 is designed to operate upon the sectional cylinders 167 and 168, the cleats 171 being so arranged that they will engage in the transverse slots or recesses 169 cut in the inner cylinder sections 168. I prefer to construct the cleats 171 as shown in Fig. 10 of the drawings in which a transverse bar 171^a is riveted or otherwise rigidly secured to the inner face of the belt 170, and an outer adjustable section 171^b formed with a curved outer face and a channeled inner face fitting loosely over the bar 171^a. Set screws 171^c pass through elongated slots 171^d and are threaded into the bar 171^a for securing the outer section 171^b in place. By loosening the screws 171^c, the section 171^b can be adjusted longitudinally of the belt 170 to accurately regulate the exact position of the belt upon the supporting cylinders, with particular reference to the positioning of the grippers carried by the belt.

35 The belt 170 is provided with a series of automatically operated grippers which are arranged in the central longitudinal plane of the belt. Each gripper consists of a curved outwardly bifurcated finger 175 projecting through a slot cut in the belt 170 and journaled at 176 between the plates or flanges 177 projecting inwardly from the inner face of the belt upon opposite sides of the slot cut through the belt. These plates or flanges 177 have journaled upon them the anti-friction rollers 178 which are designed to run upon the separated horizontal channel track bars 179 mounted beneath and parallel with the carrying portion of the belt 170. Each gripper 175 has an inwardly extending rigid arm 175^a carrying upon opposite sides the anti-friction rolls 175^b which are designed to engage the curved cam tracks 180 mounted above and adjacent to the shafts 165 and 166 for the purpose of opening and holding open the grippers at the proper points in the operation of the machine. These anti-friction rollers 175^b are designed to also engage the horizontal track bars 179 for holding the grippers in closed position while carrying the blanks, as shown clearly in Fig. 8 of the drawings.

65 The belt carrying cylinders 167 and 168 upon shafts 165 and 166 are so mounted in the machine that the upper or carrying por-

tion of the endless gripper belt 170 will be presented in the plane of feed of blanks passed forwardly by the coöperating friction wheels 151 and 152 above referred to. The carrying portion of belt 170 is arranged to be supported by the horizontal table 5 above referred to. Just above the cylinder upon shaft 165 is presented a pair of anti-friction rollers 185 freely journaled upon a curved arm 186 pivoted at 187 to the extension of guide plate 140^a. This arm 186 is yieldingly held in position by a tension spring 188. The rollers 185 which are arranged upon opposite sides of the guide plate extension 140^a are designed to engage the outwardly projecting gripper finger 175 as it is drawn beneath the rollers by the movement of the belt, and cause the closing of said gripper finger upon the forward edge of the blank, the rollers 185 holding a gripper finger in closed position long enough to insure the engagement of anti-friction rollers 175^b beneath the horizontal track bars 179. The engagement of the blank by the gripper upon the endless belt carries the blank through the side fold forming mechanism which will now be described.

Projecting upwardly from the side frames 1 and 2 in the transverse plane of the shaft 165, are the side standards 190 in which said shaft 165 is journaled. A bridge plate 191 extends across the machine and is suitably secured to the tops of the standards 190. This bridge plate 191 is of dove-tail cross section to receive upon it the adjustable slides 192 each one of which is formed with a downwardly presented dove-tail socket to fit upon said bridge piece. An adjusting screw 193, having a hand wheel 194 is freely journaled in a bracket lug 195 secured at each end of the bridge plate 191, said adjusting screws extending inwardly and passing through threaded lugs 196 projecting upwardly from the slides 192. By this means the slides 192 can be independently and accurately adjusted laterally of the machine. These slides 192 carry the downwardly extending arms 197 (indicated in dotted lines in Fig. 1 of the drawings) and secured to the lower ends of said arms 197 are the horizontally extending fold forming plates 198 having very thin outwardly presented edges to engage the side flaps of the blank as they are folded over for the purpose of accurately defining the side folds of the envelop. The purpose of the adjustment explained is to increase or decrease the width of the envelop to be formed.

200 indicates the twisted side folders of usual construction. Each of said side folders is provided with outwardly presented slotted bracket plates 201 adjustably mounted upon the bed 5 by means of set screws 202. These fold formers 200 have as usual

the horizontal portions 200^a arranged just above and parallel with the carrying portion of endless belt 170 to permit the free movement of the blank over them, and the twisted or spiral flange portions 200^b ending in the upper inwardly presented flange portions which are supported just above the supporting plates 198 to present a part of a fold forming plate 200 beneath a plate 198 and a part above said plate 198 with a sufficient free space between them to permit the passage of the folded blank therethrough. Only passing reference is made to the details of construction of these fold formers for the reason that they are well known in the art.

As the blank carried by one of the grippers on belt 170 moves through the machine, the side flap portions pass into the fold formers above horizontal portions 200^a and beneath plates 198. The side flaps coming into engagement with the twisted portion 200^b of the formers are gradually bent upwardly and over toward the center of the blank and since the twisted portion of the former at one side engages one side flap before the twisted portion of the former at the opposite side, it will be understood that the side flap of the first mentioned side will be folded in just in advance of the folding of the opposite side flap. The side flap which is the last to be folded in toward the center is the one which has been supplied with a line of paste upon its inner face at its outer edge, so that when both side flaps are properly folded in, the pasted face of the outer flap will be brought into contact with the unpasted edge of the other flap to form a center seam in the envelop blank.

Extending upwardly from the side frames 1 and 2 in transverse plane of the shaft 166 are the standards 210 in the upper ends of which is journaled a transverse shaft 211 carrying centrally between its ends a friction roll 212. Journaled upon the shaft 211 upon opposite sides of the roll 212 are the forwardly presented arms 215 connected at their forward ends by a rod 216 and having journaled in the downwardly presented lugs 217 a friction roll 220. Endless pressure belts 225 pass around the rolls 212 and 220 and engage the upper face of the endless belt 170 in lines corresponding with the folded edges of the blank after it has passed through the fold forming mechanism above described. These pressure belts 225 press down the folded side edges of the blank after it has passed said forming mechanism. These belts 225 can be adjusted inwardly or outwardly upon their rolls by any suitable means (not shown). The shaft 211 is provided with a sprocket wheel 226 driven by a sprocket chain 227 operated from a suitable driving sprocket 226^a upon the shaft 226^b or other suitable rotating part of the machine. The shaft 226^b carries an interme-

diate gear 226^c of the main gear train by which it is driven. It will be observed that the arms 215 can be raised upwardly when it is desired to have access to the blank or endless belt 170 beneath the pressure belts 225.

After passing beneath the pressure belts 225 the gripper 175 releases the blank and by the engagement of the blank at its edges between belts 225 and 170, it is continued rearwardly over the guide plate 230 into the bite of upper and lower feed rollers 235 and 236 mounted upon suitable transverse shafts and driven by gearing with other parts of the machine in a manner well understood. A curved guide arm 240 is supported above the plane of blanks between the rollers 212 and 235 to confine the leading edge of the blank in the event of any tendency to bend upwardly. The blank with the side flaps folded and sealed in the manner explained is passed by the rollers 235, 236 to the final creasing and bottom flap pasting and forming mechanisms constructed as will now be explained.

245 and 280 are transverse shafts suitably journaled in the side frames of the machine above and below the plane of travel of the blanks. These shafts carry the upper and lower members of the creasing and end flap forming mechanisms. Mounted upon the lower shaft 245 adjacent to its center are the radial arms 246 carrying the final gripper mechanism and the female member of the end flap creasing mechanism. Means such as set screws 246^x adjustably secure arms 246 upon shaft 245. These arms 246 are formed with enlarged heads having outwardly presented rectangular slots or recesses 247 in which are mounted the transversely extending rectangular creasing bar 248 and pressure bar 248^a. The creasing bar 248 is formed in its outer face with a transverse groove or recess 249 constituting the female member of the end flap creasing mechanism. Slots 250 are formed between the bars 248 and 248^a through which extend the gripper arms 251, each having an inwardly projecting gripper finger 252 (see Fig. 18). These gripper arms 251 projecting approximately radially to the shaft 245, are adjustably mounted (by means of bolts 255 passing through slots 256) upon the transversely movable gripper bars 258 which have pin and slot connections at their inner ends as shown in dotted lines at 259 in Fig. 18 of the drawings. The gripper bars 258 are capable of moving transversely of the machine and radially of their carrying frame. Springs 260 connect the gripper bars 258 with the radial arms 246 for giving the gripper bars a tendency to move toward the sides of the machine, while springs 261 connect the gripper bars 258 with arms 246 to yieldingly hold said gripper bars 258.

pers against the creasing bar 248 and pressure bar 248^a.

Secured to each side frame 1 and 2 adjacent to the ends of the shaft 245 are the stationary cams 265, in engagement with which the ends of gripper bars 258 operate. Each cam 265 comprises a face cam for causing one of the gripper bars to move inwardly and outwardly transversely of the machine, and a similar cam for moving the gripper bars radially with reference to shaft 245. While these cams 265 independently act upon the two gripper bars, it will of course be understood that they are arranged to act in unison so that the two gripper bars will operate simultaneously to cause the grippers mounted upon them to engage and disengage the blanks. The detail construction of this final gripper mechanism is partly shown in Fig. 7 of the drawings in connection with the machine for forming a central seam envelop, but is more fully shown in Fig. 18 of the drawings, illustrating the modified arrangement of the machine for making side seam envelops. So far as this gripper mechanism is concerned, its construction is the same for either form of machine.

The shaft 245 also carries two or more segmental frame pieces 270 adjustably mounted upon the shaft by suitable means such as set screws 270^a. Each frame 270 is formed in its periphery with a plurality of transversely arranged dove-tail sockets or pockets 271 to receive a creasing bar 272 formed with a creasing slot 273 and held in place by means of set screws 274. This creasing bar 272 is designed to coöperate with a similar creasing bar mounted in a similar frame above the plane of feed of the blanks as hereinafter explained. By forming the segmental frames 270 with a plurality of receiving sockets 271, it will be understood that the position of the creasing bar 272 can be adjusted upon the frame to regulate its distance circumferentially from the lower creasing member 249 above referred to. These segmental members 270 are preferably arranged in parallel longitudinal vertical planes of the machine as close as practicable to the parallel planes of gripper fingers 252 above referred to. The grippers and the frames are both adjustable either circumferentially of the carrying frame or transversely of the machine to suit not only different sizes of envelops with regard to width, but also with regard to length. When the folded edges of the blank are engaged by these grippers 252, said edges are supported upon the peripheries of segmental frame members 270 as the frame rotates for delivering the envelop in the manner hereinafter more fully explained. Coöoperating with the arms 246 and segmental frame members 270, are aux-

iliary segmental frame members 275 (see Fig. 7) which are also adjustably mounted upon the shaft 245 in different longitudinal vertical planes from the other parts of said rotating frame for the purpose of circumferentially bridging the space between the heads of arms 246 and the segmental frame members 270, so that the envelop in process of formation will be properly supported during the final stages of the operation. 75

The shaft 280 above referred to carries the upper sectional rotary frame which cooperates with the similarly formed frame upon shaft 245 just described. This upper frame includes a plurality of radial arms 281, the segmental frame members 285 and the auxiliary segmental frame members 290. All of these parts are adjustably mounted both transversely and circumferentially upon the shaft 280, the arms 281 being adjustably secured by means such as set screws 281^a, the members 285 by means such as set screws 285^a, and the members 290 by means such as set screws 290^a. 85

The arms 281 are formed with bifurcated outer ends and secured to faces 281^a of said arms is a transversely extending creasing blade 282 which is designed to engage the transverse slot or groove 249 formed in the bar 248 of the lower rotary frame. The arms 281 and 246 are adjusted to bring the blade 282 and slot 249 into accurate engagement to form the transverse crease in the bottom flap of the envelop as the partly folded envelop is brought into position between said creasing members. 90

283 is a rock shaft journaled in projections of arms 281, and 284 is a transversely extending spring pasting plate secured to the rock shaft 283. 100

286 is a rock arm projecting from rock shaft 283 and carrying an anti-friction roller 287 which runs in peripheral engagement with a stationary cam 288, secured to one of the side frames of the machine. If desired I may provide two rock arms 286 and two cams 288 at opposite sides of the machine. 110

The pasting blade or plate 284 is supported approximately tangentially to the path of rotation of the rotary frame upon which it is mounted and its operating means cause it to move inwardly and outwardly transversely of this path of rotation of the supporting frame. The blank creasing members 249 and 282 engage the blank in rear of the end flap and support the blank with the end flap projecting freely from the creasing mechanism in the path of the pasting blade. 115

289 is a paste receptacle mounted upon a transverse bar 289^a supported by auxiliary side brackets 289^b detachably secured to the main side frames 1 and 2 of the machine. A pasting roll 291 operates in the paste re- 130

ceptacle 289 and is journaled in bracket bearings formed partly in the auxiliary brackets 289^b and partly in the main side frames of the machine. This paste roll 291 carries upon one of the projecting ends of its shaft a sprocket wheel 292 over which passes a sprocket chain 293 driven by a smaller sprocket wheel 294 keyed to the end of shaft 280.

19 The rotation of the sectional frame carried by shaft 280 in the direction indicated by the arrow in Fig. 7 will cause the spring paster plate 284 to be wiped against the rotating periphery of paste roll 291 to take 15 therefrom a film of paste, and when completing its rotation to the position shown in Fig. 7, will wipe against the projecting bottom flap of the envelop while the same is momentarily held between the two creasing 20 members 249 and 282, said wiping contact with the flap applying sufficient paste to the bottom flap to cause it to seal the end of the envelop when it is folded over onto the already centrally seamed blank.

25 The segmental frame members 285 are of the same construction as the above described segmental members 270 of the lower rotating frame. These members 285 are formed with the dove-tailed transverse sockets or 30 pockets 285^a in which may be removably mounted the creasing bar 300 carrying a creasing blade 301. Since the creasing bar 300 can be placed in any one of the series of sockets or pockets 285^a, its distance circumferentially from the creasing blade 282 can be adjusted. The blade 301 is so positioned upon its carrying frame that it will meet and engage the transverse slot or 35 groove 273 in the creasing bar 272 of the lower frame. The coöperation of these two creasing members imparts the final transverse fold in the top flap of the blank when the envelop is formed with said top flap. When the envelop is not provided with a top 40 flap, the creasing bars 272 and 300 can be removed from their frames.

The auxiliary segmental frame pieces 290 are of the same construction and for the same purpose as the auxiliary pieces 275 of the lower rotating frame, the position of 50 members 290 upon the upper frame being adjusted to correspond with the position of the members 275 upon the lower frame, so that the blank will be engaged between said 55 members as these two frames rotate in unison.

The two rotating frames above and below the plane of feed of the blank as just described are driven by means of gears upon 60 the projecting ends of their shafts 245 and 280, which gears are driven through idler wheel from the shaft 166 of the machine.

The blank with the centrally formed seam is passed by the coöperating rollers 235, 236 65 into position above the lower rotating frame

on shaft 245 to have the transverse crease or score formed in the bottom flap by the arrangement of creasing members 249 and 282. Simultaneously with this operation the bottom flap which projects beyond the creasing members is pasted by the pasting device 284 and also simultaneously with this operation the gripper fingers 252 are brought into engagement with the folded side edges of the partly completed envelop. As these 70 frames continue to rotate, the envelop (with bottom flap bent upwardly slightly because of its crease) is carried past a cylindrical bar 305 supported upon arms 306, and said bar folds over the pasted bottom flap upon 75 the creased line and the arms 306 engage said flap and hold it bent inwardly until the bottom fold is engaged by roller 310 to cause the bottom flap to adhere to the body of the envelop. The grippers 252 hold on to the 80 envelop until the blank is engaged by the transverse roller 310 which is grooved at 85 310^a to fit over grippers 252, after which the envelop is passed through the delivery rollers 315, 316 and delivered by them into 90 a packing box 320 operating in the usual manner.

The exact position of the rollers 315 and 316 beneath roller 310, shown in the drawings, is not essential, since the flexibility of 95 the envelops and the direction of rotation of rollers will accurately lead the advancing end of the envelops into the bite of rollers 315 and 316, without the assistance of guiding means.

The auxiliary segmental frame portions 275 and 290 are correspondingly arranged above and below the path of the envelop so as to engage the same and assist the grippers in the forward feed. The bottom flap seam 100 105 is pressed for securely sealing by the rollers 310, 315 and 316, the roller 310 acting against pressure bar 248^a and the roller 315 being formed with a longitudinal groove 315^a to bridge over the inner edge of bottom flap 110 to escape any glue which may be squeezed out by the pressure.

In Figs. 11 to 16, both inclusive, I have illustrated the several stages in the formation of a center seam envelop. Fig. 11 115 shows the blank. This blank B is fed from the pile by the automatic feeding machine with the bottom flap B' leading. As the blank passes up around the gripper cylinder 125 a line of paste a is applied to the 120 inner face of one side flap as shown in Fig. 12. The blank then passes through the side fold forming mechanism under the action of the endless gripper belt 170 to fold and seal the two side flaps to form a center seam shown 125 at c in Fig. 13. The side folds are completely creased by the action of the pressure belts 225 and the blank is then passed to the final creasing and pasting mechanism to receive the transverse crease d and transverse 130

line of paste *e* upon the bottom flap as shown in Fig. 14. The bottom flap is then folded over to seal the bottom of the envelop as illustrated in Fig. 15, and finally, in the case of envelopes having top flaps, the top flap crease *f* shown in Fig. 16, is formed.

The main features of my improved machine can be employed with slight changes or modifications to produce various styles 10 of envelopes. I have shown in Figs. 17 and 18 of the drawings certain modifications for making side seam envelopes such as illustrated in the diagrammatic views of Figs. 19 to 23, both inclusive. For the manufacture 15 of the side seam form of envelop, I remove or put out of operation the preliminary pasting device 156 and the final pasting device 291. These parts can be removed by detaching the pasting rolls and pasting 20 boxes from the frame, without the necessity of the removal of the grooved wheel 155 which coöperates with the preliminary pasting device, or the pasting blade 284 which coöperates with the final pasting device, the 25 pasting blade 284 going through the motions without performing any function when pasting roll 291 is removed. I also remove from the first form of the machine the final creasing bars 272, 300, the bottom 30 flap turning bar 305, and the sealing and feeding rollers 310 and 315. The remaining parts of the machine may remain the same, although I prefer to employ in addition to the segmental frames 270 upon shaft 35, the grooved segmental frames 330 to co-operate with a different form of pasting device as will presently be explained. Frames 330 are preferably formed with divided hubs 330^a secured upon shaft 245 by screws 40 or bolts as shown in Fig. 17 of the drawings. The paste supporting bracket frame 289^b having been removed, a modified form of bracket frame 335 is secured to the flanges at the ends of the side frames as 45 shown in Fig. 17. This auxiliary frame 335 supports a paste receptacle 336 in which operates a paste roll 337, which may be the same roll heretofore indicated by reference 291. The shaft of this roll 50 337 which is journaled in the frame 335 may be driven in any suitable manner such as by a sprocket wheel 337^a driven by sprocket chain 337^b and sprocket wheel 337^c on the projecting end of shaft 280. 55 Arms 338 are journaled upon the shaft of paste roll 337 and a shaft 339 is freely journaled in said arms 338 and is provided at its end with a gear 340 meshing with a gear wheel upon the end of shaft 245. The 60 shaft 339 carries two paste applying segments 345 which are formed with peripheral ribs adapted to operate in the peripheral grooves of segments 330 upon shaft 245 to press the inwardly folded side flanges 65 of the blank into the grooves of said seg-

ments to better apply lines of paste. The paste applying segments 345 rotate in peripheral engagement with the rotating paste roll 337 to take up a film of paste therefrom preparatory to applying it to the 70 edges of the blank. Segments 345 are adjustably mounted upon shaft 339 by means of the sectional hub 345^a and screw bolts securing said hub sections upon the shaft as shown in Fig. 17 of the drawings. In this 75 form of attachment, I prefer to provide a different envelop delivery mechanism comprising belt rollers 350 and 351 supporting delivery belts 352 which receive the completed envelopes from the under rotating 80 frame and carries them through transverse rollers 355 and 356 from which they are deposited into a suitable receptacle.

In the operation of this modified form of the machine, it will be understood that the blanks C of the form shown in Fig. 19, are taken from the automatic feeding machine by the gripper cylinder, with the long bottom flap C' leading. The blank is carried through the machine and the narrow side flaps *h* are folded inwardly by the side fold forming mechanism into the position shown in Fig. 20. The blank with side folds is then passed to the control of the upper and lower rotating frames upon shafts 245 95 and 280 with the long bottom flap C' projecting entirely beyond the line of crease *k*. The creasing devices 249, 282 then engage the blank to form the crease *k* at which moment the flap C' extends loosely downwardly 100 around the lower rotating frame upon shaft 245 and the paste applying segments are just approaching their active position. The infolded side flaps *h* being then gripped by the grippers 252 at point *p* (see Fig. 21) 105 and the paste applying segments 345 coming into engagement with the blank along the infolded flaps *h*, apply lines of paste upon said flaps as shown in Fig. 22. As the blank with double line of paste is carried 110 downwardly by the lower rotating frame, the forwardly projecting long flap C' will rest upon the roller 316, and if desired may be partly supported in place by a deflector plate 360. The grippers in this form of the machine hold on to the blank until it is engaged between the segments 270 and the belt rollers 350 with the result that the long flap C' will be pressed at its edges against the glued surfaces of inwardly folded side flaps *h* and the completed envelop carried by belt 352 to the delivery rollers 355, 356. It will 115 of course be understood that in this side seam form of envelop, an end flap can also be provided by cutting the same upon the blank and leaving in operation the final transverse creasing mechanism 272, 300. 120

Each of the several pasting devices is constructed and arranged as above described 125 so that it can readily be placed upon or re-

5 moved from the machine or otherwise adjusted into and out of operative position, to thereby provide individual means for placing each pasting device into and out of operation. Such construction facilitates the changing of the machine to suit the type of envelop to be manufactured.

10 In describing the operation of my improved machine, I have referred to the manufacture of two types of envelops which I have distinguished as the center seam envelop and the side seam envelop. It will of course be understood that the characteristic of what I have termed the center seam 15 envelop is the single longitudinally extending seam for uniting two inwardly folded side flaps into a blank. It will readily be understood that by the proper adjustment of the operative parts of the machine, this 20 single longitudinal seam for uniting the inwardly folded side flaps of the blank may be formed in the direct central longitudinal line of the envelop, or it may be formed upon either side of this central longitudinal 25 line of the envelop by previously preparing the blanks with one side flap wider than the other. The side seam form of envelop referred to by me may also be slightly modified to have the side seams directly at the longitudinal edges of the envelop, or farther in 30 from the edges.

What I claim is:

1. In an envelop machine, the combination of suitable feeding devices for conveying envelop blanks, suitable side fold forming mechanism, and suitable transverse creasing mechanism, with a center seam pasting device, and the side seam and bottom flap pasting devices, said side seam and 40 bottom flap pasting devices being interchangeable with each other, whereby the machine may be arranged to produce different styles of envelops.

2. In an envelop machine, the combination of suitable feeding devices for conveying envelop blanks, suitable side fold forming mechanism, and suitable transverse creasing mechanism, with the center seam pasting device, the side seam pasting device, 45 and the bottom flap pasting device, said side seam and bottom flap pasting devices being interchangeable with each other, and individual means for readily placing each of said pasting devices into or out of operation, 50 whereby the machine can be employed to produce different styles of envelops.

3. In an envelop machine, the combination with suitable feeding devices for conveying envelop blanks, suitable side fold 60 forming mechanism, and transverse creasing mechanism adapted to crease an end flap and temporarily support the blank with the creased flap projecting freely from the creasing mechanism, with a bottom flap pasting device mounted to rotate free from contact

with the creasing mechanism and adapted to apply paste to a projecting end of a creased flap while the blank is held by the creasing mechanism.

4. In an envelop machine, the combination with suitable feeding devices for conveying envelop blanks, suitable side fold forming mechanism, and transverse creasing mechanism adapted to crease an end flap and temporarily support the blank with the creased flap projecting freely from the creasing mechanism, with a bottom flap pasting device including a paste supply roller, a rotary frame, a flap pasting blade pivoted upon said frame, and a controlling cam moving said blade alternately into engagement with the paste supply roller and the projecting end of an envelop flap held in the creasing mechanism.

5. In an envelop machine, the combination with suitable feeding devices for conveying envelop blanks, suitable side fold forming mechanism, and transverse creasing mechanism adapted to crease an end flap and temporarily support the blank with the creased flap projecting freely from the creasing mechanism, with a center seam pasting device, and a bottom flap pasting device comprising a rotary frame, a rock shaft journaled in said frame, a flap pasting 95 blade upon said rock shaft, a paste supply roller, a controlling cam, and a rock arm upon said rock shaft operating in engagement with said cam, the pasting blade being mounted to rotate free from contact with the creasing mechanism and alternately engage the paste supply roller and the projecting end flap held by the creasing mechanism.

6. In an envelop machine, the combination of suitable feeding devices for conveying envelop blanks, suitable side fold forming mechanism, a suitable transverse creasing mechanism including the relatively movable creasing blade and creasing bar 105 adapted to crease and support a blank with the flap projecting freely from the creasing mechanism, with a bottom flap pasting device including a flap pasting blade mounted to move with the creasing mechanism free from contact therewith and means for supplying paste to the pasting blade and means for moving the pasting blade into contact with the free end of a projecting flap while it is held by the creasing mechanism.

7. In an envelop machine, the combination of suitable feeding devices for conveying envelop blanks, suitable side fold forming mechanism, and suitable transverse creasing mechanism, with a bottom flap pasting device including a paste supply roller, a rotary frame, a flap pasting blade pivotally mounted adjacent to the periphery 125 of said rotary frame and extending approximately tangentially of the path of rotation 130

of said frame, means moving said blade transversely of said path of rotation to cause it to alternately engage with said paste supply roller and an envelop flap, and 5 blank engaging and supporting means arranged to engage and support a blank in rear of its bottom flap with the flap projecting freely into the path of said blade.

8. The combination, in an envelop machine, of the side fold forming mechanism, the transverse flap creasing mechanism, and suitable paste applying devices, with an endless conveyer belt provided with a series 10 of grippers arranged in the central longitudinal line of said belt, means for supporting and driving said belt, gripper controlling track bars arranged beneath and parallel with the carrying portion of said belt, an arm projecting inwardly from each gripper, and means for closing said grippers and holding them closed until said gripper arms engage beneath said track bars, whereby the grippers are securely held in closed 15 position for conveying sheets.

25 9. The combination, in an envelop machine, of the side fold forming mechanism, the transverse flap creasing mechanism, and suitable paste applying devices, with an endless conveyer belt provided with a series 30 of grippers, means for supporting and driving said belt, gripper controlling track bars arranged beneath and parallel with the carrying portion of said belt, an arm projecting inwardly from each gripper, and a 35 spring pressed roller adapted to engage and close said grippers and hold them closed until said gripper arms engage beneath said track bars.

40 10. The combination, in an envelop machine, of the side fold forming mechanism, the transverse flap creasing mechanism, and suitable paste applying devices, with an endless conveyer belt provided with a series of 45 grippers, means for supporting and driving said belt, track bars arranged beneath and parallel with the carrying portion of said belt, anti-friction rollers mounted upon the inner face of said belt and adapted to travel 50 upon said track bars for supporting the carrying portion thereof, an arm projecting inwardly from each gripper, stationary curved cam tracks adapted to engage said gripper arms for opening said grippers, and means for closing said grippers and 55 holding them closed until said gripper arms engage beneath said track bars.

60 11. The combination, in an envelop machine, of the side fold forming mechanism, the transverse flap creasing mechanism, and suitable paste applying devices, with an 65 endless conveyer belt provided with a longitudinal series of grippers, means for supporting and driving said belt, track bars arranged beneath and parallel with the carrying portion of said belt, anti-friction rollers

mounted upon the inner face of said belt and adapted to travel upon said track bars for supporting the carrying portion thereof, an arm projecting inwardly from each gripper, means for opening said grippers, and a 70 spring pressed roller supported in the path of said grippers and adapted to engage and close said grippers and hold them closed until said gripper arms engage beneath said track bars.

75

12. The combination, in an envelop machine, of the side fold forming mechanism, the transverse flap creasing mechanism, and suitable paste applying devices, with an endless conveyer belt provided with a longitudinal series of grippers, means for supporting and driving said belt, track bars arranged beneath and parallel with the carrying portion of said belt, anti-friction rollers mounted upon the inner face of said belt and adapted to travel upon said track bars, an arm projecting inwardly from each gripper and carrying an anti-friction roller, stationary curved cam tracks adapted to engage said gripper arms for opening said grippers, 80 a spring pressed roller supported above the plane of feed of blanks in position to engage the grippers and force them into closed position and cause said gripper arms to engage beneath said track bars, and means for supplying blanks into position to be taken by said grippers.

85

13. In an envelop machine, the combination of side fold forming mechanism, transverse flap creasing mechanism, and suitable paste applying mechanism, with means for conveying envelop blanks successively through said machine, said conveying means including a broad endless conveying belt, supporting and driving cylinders for said belt, transverse slots formed in said cylinders, transverse cleats secured to the inner face of said belt and engaging said cylinder slots, each of said cleats consisting of a member rigidly secured to the belt and a channeled wear member fitting over said rigidly attached member and adjustable thereon longitudinally of the belt.

95

14. In an envelop machine, the combination of side-fold forming mechanism, transverse flap creasing mechanism, and suitable paste applying mechanism, with means for conveying envelop blanks successively through said mechanism, said conveying means including a broad endless conveying belt, supporting and driving cylinders for said belt, transverse slots formed in said cylinders, transverse cleats secured to the inner face of said belt and engaging said cylinder slots, each of said cleats comprising a bar rigidly secured to the inner face of said belt, and a curved wear member formed with a channel in which said rigidly attached member is loosely inclosed, and set screws seated in said rigidly attached mem- 115

ber and passing through slots formed through said wear members and elongated in the direction of travel of the belt, whereby said wear members can be adjusted longitudinally of said belt.

15. The combination, in an envelop machine, of the side fold forming mechanism, the transverse flap creasing mechanism, and suitable paste applying devices, with an endless conveyer belt provided with a longitudinal series of grippers, each of said grippers projecting through a suitable opening in the belt and pivoted upon inwardly presented brackets, supporting and driving cylinders for said belt, longitudinal track bars arranged beneath and parallel with the carrying portion of said belt, anti-friction rollers journaled upon the inwardly presented brackets in position to travel upon said track bars, curved cam tracks arranged adjacent to the belt carrying cylinders, a gripper operating rock arm secured to each gripper and provided with an anti-friction roller adapted to travel upon said curved cam tracks to open the grippers and hold them in open position, and to engage and travel upon said longitudinal track bars to hold said grippers in closed position, means for engaging said grippers to move them into closed position and hold them closed while said gripper operating rock arms are moving out of engagement with one of said curved cam tracks and into engagement with said longitudinal track bars, and means for supplying blanks in position to be engaged by said grippers.

16. In an envelop machine, the combination of suitable side fold forming mechanism, suitable transverse flap creasing mechanism, suitable pasting mechanism, and a conveyer belt for conveying successive blanks through said mechanisms, with a rotary gripper cylinder, grippers mounted upon said cylinder and formed with blank engaging fingers and curved registering faces adjacent to said engaging fingers, means for presenting the leading edges of successive blanks into position to be taken by said cylinder grippers, means for opening and closing said grippers, and means for transferring blanks from said gripper cylinder to said conveyer belt.

17. In an envelop machine, the combination of suitable side fold forming mechanism, suitable transverse creasing mechanism, suitable pasting mechanism, and a conveyer belt for conveying successive blanks through said mechanisms, with a rotary gripper cylinder, grippers mounted upon said cylinder and adjustable circumferentially thereof, means for presenting the leading edge of successive blanks into position to be taken by said cylinder grippers, means for opening and closing said grippers, and means for transferring blanks

from said gripper cylinder to said conveyer belt.

18. In an envelop machine, the combination of suitable side fold forming mechanism, suitable transverse creasing mechanism, suitable pasting mechanism, and a conveyer belt for conveying successive blanks through said mechanisms, with a rotary gripper cylinder formed of independently adjustable wheel sections capable of transverse and circumferential adjustment, adjustably mounted grippers upon said cylinder, means for presenting the leading edges of successive blanks into position to be taken by said cylinder grippers, means for opening and closing said grippers, and means for transferring blanks from said gripper cylinder to said blank conveyer.

19. In an envelop machine, the combination of suitable side fold forming mechanism, means for conveying blanks through said side fold forming mechanism, and suitable paste applying mechanism, with a transverse creasing mechanism comprising coöperating rotary segmental frames arranged above and below the plane of feed of blanks and formed with a plurality of transverse sockets or pockets, and creasing bars removably mounted in said transverse sockets or pockets, for the purposes set forth.

20. In an envelop machine, the combination of suitable side fold forming mechanism, means for conveying blanks through said side fold forming mechanism, and suitable paste applying mechanism with a transverse creasing mechanism comprising rotary segmental frames arranged above and below the plane of feed of blanks, said segmental frames carrying coöperating members of two sets of transverse creasing devices, the members of one set of said creasing devices being adjustable circumferentially of said frames with relation to the others.

21. In an envelop machine, the combination of suitable side fold forming mechanism, means for conveying blanks through said side fold forming mechanism, and suitable paste applying mechanism, with a transverse creasing mechanism comprising coöperating rotary segmental frames adjustable circumferentially and arranged above and below the plane of feed of blanks and formed with a plurality of transverse sockets or pockets, and creasing bars removably mounted in said transverse sockets or pockets for the purposes set forth.

22. In an envelop machine, the combination of suitable side fold forming mechanism, means for conveying blanks through said side fold forming mechanism, and suitable paste applying mechanism, with a transverse creasing mechanism comprising rotary segmental frames arranged above and below the plane of feed of blanks, said

- frames carrying coöperating bottom flap creasing devices and formed with a plurality of transverse sockets or pockets, and coöperating creasing bars removably mounted in said transverse sockets or pockets, whereby said removable creasing bars may be mounted at different distances circumferentially from said bottom flap creasing devices.
- 10 23. In an envelop machine, the combination of suitable side fold forming mechanism, means for conveying blanks through said side fold forming mechanism, and suitable paste applying mechanism, with a transverse creasing mechanism comprising rotary segmental frames arranged above and below the plane of feed of blanks, each of said rotary frames comprising sections which are adjustable circumferentially with relation to each other, coöperating bottom flap creasing members mounted upon sections of said frames, and coöperating top flap creasing members mounted upon other sections of said frames.
- 15 24. In an envelop machine, the combination of suitable side fold forming mechanism, means for conveying blanks through said side fold forming mechanism, and suitable paste applying mechanism, with a transverse creasing mechanism comprising rotary segmental frames arranged above and below the plane of feed of blanks, each of said rotary frames comprising sections which are adjustable circumferentially with relation 20 to each other, coöperating bottom flap creasing members mounted upon sections of said frames, coöperating top flap creasing members mounted upon other sections of said frames, and automatically operated grippers mounted upon said lower rotary frame

in position to engage the side folded edges of the partially formed envelop.

25. In an envelop machine, the combination of suitable side fold forming mechanism, means for conveying blanks through said side fold forming mechanism, suitable paste applying mechanism, and transverse creasing mechanism, with a rotary cylinder and gripper mechanism mounted upon said cylinder and including a sectional gripper bar movable transversely and radially upon said cylinder, gripper fingers mounted upon the sections of said bar in position to oppositely engage a blank upon the periphery of said cylinder, the two sections of said gripper bar being capable of relative movement transversely of said cylinder, and cams for operating said gripper bar.

26. In an envelop machine, the combination of suitable side fold forming mechanism, means for conveying blanks through said side fold forming mechanism, transverse creasing mechanism, and suitable paste applying mechanism, with a gripper cylinder, a transversely and radially movable gripper bar mounted upon said cylinder and formed of transversely alined sections having driving connection with each other, grippers carried by said bar sections, springs tending to move said sections apart transversely of said cylinder, springs tending to hold said sectional gripper bar inwardly against radial movement and cams for imparting radial and transverse movements to said sectional gripper bar.

MATTHEW VIERENGEL.
